LADDER STOOL

Charles W. Harrison, Warsaw, Ind., assignor to
 Arnolt Corporation, Warsaw, Ind., a corpora-
 tion of Indiana

Application October 17, 1950, Serial No. 190,595

4 Claims. (Cl. 228—30)

1

This invention relates to household furniture and particularly to convertible stools adapted for kitchen and other household use.

Stools of the aforesaid character are usually made with a seat supported by four downwardly projecting legs, and between the front legs on which a tiltable ladder of multiple step structure is supported on a transverse horizontal pivot for movement between a lower operative position wherein the step structure is located in a forwardly projecting operative or step-like relation and a raised inoperative position wherein the step structure is disposed in a protected and out-of-the-way relation in the space between the legs and beneath the seat. Such ladder stools as heretofore constructed have been objectionable either by reason of lack of stability or because of the high cost involved where the desired degree of stability was attained, and it is the primary object of this invention to improve and simplify the construction of such stools in such a way that stability and rigidity of structure may be attained without excessive cost.

In the use of stools of the aforesaid character it is recognized that the provision of a back on such stools would be advantageous, but in the past, the provision of a back has been relatively complicated and has been considered to be too expensive because it required the manufacture of two different stool structures. It is therefore another object of this invention to enable a ladder stool to be so constructed and arranged that it may be made either with or without a back structure and a related object is to enable the back on such a stool to be readily and easily put in place without modification of the parts used in a backless stool.

Other and further objects of the present invention will be apparent from the following description and claims and are illustrated in the accompanying drawings, which, by way of illustration, show a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

In the drawings:

Fig. 1 is a perspective view of a ladder stool embodying the invention;

Fig. 2 is a perspective view of the frame elements that make up the stool, certain of the

2

parts being shown in a separated or spaced relation;

Fig. 3 is a fragmentary vertical sectional view showing the pivot structure for the ladder;

Fig. 4 is a fragmentary view showing the way in which the ladder is supported;

Fig. 5 is a plan view of the frame; and

Fig. 6 is a side view of the frame.

For purposes of disclosure the invention is herein illustrated as embodied in a ladder-stool 10 having a seat 11, tubular metal front and rear legs 12 and 13 secured to and supporting the seat 11, a spreader bar structure 14 connecting and spacing the legs, and a pivoted step structure 15 disposed between the front legs 12 for swinging movement between the forwardly projecting operative position of Fig. 1 and a protected or stored position beneath the seat 11, as indicated in dotted outline in Fig. 6; and under the present invention as hereinafter described, the stool 10 may be provided with a back 16 in a simple manner which does not involve change or revision of the main stool structure.

The rear legs 13 are formed as integral elements of a generally U-shaped member 113, that is formed from a single piece of tubing as shown in Fig. 2 so as to afford a horizontal front cross bar 113A joined at its opposite ends by smooth bends or arcuate portions 113B to parallel rearwardly projecting portions 113C, and at their rear ends, the portions 113C are joined by downward bends 113D to the upper ends of the rear legs.

The front legs 12 are separately formed from tubing in a generally inverted L-shape, as shown in Fig. 2, thus to afford an upper rearwardly projecting portion 112C that is joined at its forward end to the upper end of the related leg 12 by a relatively large radius downward bend 112B. The portions 112C of the legs 12 are disposed along the inner or adjacent sides of the portions 113C and are rigidly secured thereto as by brazing or welding, and the relation is such that the open rear ends of the portions 112C terminate forwardly of the bends 113D, thus to be located in a concealed relation to the seat 11 which is secured to the leg structure by screws 115, Fig. 4, that are passed upwardly through opening 112E formed in the portions 112C.

The spreader bar 14 is formed from a single elongated piece of material which in the present case is afforded by tubing bent to a generally U-shaped form to afford a rear bar 114R that is joined by forward horizontal bends 114A to the rear ends of parallel forwardly projecting side bars 114S, and at their forward ends the side

bars 114S are bent inwardly at 114F to afford aligned projecting bearing ends 114B that face toward each other to provide pivoted bearing supports for the step structure 15 as will be described. Where the spreader bar 14 is formed from tubing, the ends that thus face each other are open so that their internal surfaces may afford bearings. The spreader bar structure 15 is disposed within the space between the several legs 12 and 13, and in a horizontal position, and the bends 114A are secured rigidly to the respective rear legs 13 as by brazing or welding, while the bends 114F are similarly secured to the front legs 12.

The step structure 15 is formed from tubing to afford a mounting for a lower step 15L and an upper step 15U, as shown in Fig. 1, the proportioning of the parts being such that the lower step 15L is disposed at a height equal to substantially one-third of the height of the seat 11, while the upper step 15U is located at about two-thirds of the height of the seat 11. Thus the step structure comprises a pair of similar frame members 115 formed from tubing to provide an upwardly extending leg 115L that is of a length substantially equal to the spacing of the spreader bar 14 from the lower ends of the legs 12 and 13. At its upper end each leg 115L is joined by a rearward bend 115A to a horizontal step support portion 115B which projects rearwardly for a distance substantially equal to twice the width of the step 15L, and in the forward part of the portion 115B, openings 115C are provided through which attaching screws 115D may be extended upwardly to secure the step 15L in position. At its rear end each portion 115B is joined by an upward bend 115E to a riser portion 115F, and at its upper end each riser portion is joined by a forward bend 115G to the rear end of a forwardly projecting upper step support portion 115H. Each step support portion 115H extends forwardly for a distance, substantially equal to the width of the upper step 15U which is secured in place on the portion 115H by screws 115J extended upwardly through openings 115K formed in the portion 115H.

In assembly of the members 115, a tie bar 115T is extended across the outer, or rearward and lower, sides of the bends 115E and is rigidly secured thereto as by brazing or welding. This is done in such a way that the corresponding parts of the two members 115 are parallel, and the tie rod 115T is disposed so as to be perpendicular to the spaced planes in which members 115 are located. The arrangement is such that the tie bar 115T is somewhat longer than the distance between the open bearing ends 114B of the spreader 14, and the members 115 are spaced from each other in a distance such that the ends of the tie bar 115T project somewhat beyond the members 115, thus to afford projecting bearing elements which are in the form of journals 215J. Under the present invention the tie bar 115T is made from a circular stock material such as metal tubing that has an outer diameter just slightly less than the inner diameter of the tubing from which the spreader 14 is made, and with this arrangement the projecting journals 215J may be inserted into the open bearing ends 114B of the spreader 14, thus to afford a pivotal mounting for the step structure 15. It will be obvious of course that this pivotal relation is attained by reason of the telescoped relation of the elements 114B and 215J, and that this relation might be reversed if desired. Moreover it will be clear that in either of

such telescoped relationships, the inner member might be of solid cross section rather than tubular. This insertion of the journals 215J into the bearing end 114B may be readily accomplished by spreading the front legs 12 against the resilient action of the spreader 14, and in practice this resilient force is found to be ample to retain the bearings 114B in engagement with the journals 215J. The step structure 15 may thus be positioned in its operative relation of Fig. 6, or may be pivoted to its dotted line position 15A of Fig. 6, where the end caps of the legs 115L rest against a stop such as the front bar 113A.

As hereinabove pointed out, the present invention provides for production of the stool 10 either with or without the back 16, and in accomplishing this the back 16 is mounted on a pair of similar L-shaped back supports 116 formed from tubular metal to afford a vertical portion 116A and a horizontal portion 116B joined in each instance by a forward bend 116C which connects the lower end of the portion 116A to the rear end of the portion 116B. The vertical portion 116A has transverse or horizontal openings 116D therein for use in securing the back 16 in position thereon, while each portion 116B has a vertical opening 116E therein for use in fixing the back in position, as will be described.

Under the present invention the tubular stock from which the back supports 116 are formed is selected to have an outer diameter equal to the inner diameter of the tubular stock from which the legs 12 are formed, and hence when a back 16 is to be used, the portions 116B may be inserted forwardly into the open rear ends of the portions 112C, as shown in Fig. 4, and when the openings 116E are aligned with the rear opening 112E, the same screws 118 may be passed upwardly through the aligned sets of openings so that the back 16 is secured in place as an incident to the securing of the seat 11 on the leg structure.

It will be obvious, of course, that the upper ends of the back support elements 116A may be in the form shown so as to be closed by conventional end closure caps, or may be of a flattened or fishtail form. Moreover, it will be clear that the lower ends of the legs, and the ends of the members 115 may be similarly closed by decorative end caps of conventional construction.

From the foregoing description it will be evident that the present invention affords a new and improved stool structure wherein a single basic unit may be used to afford stools with or without backs, and wherein rigidity of leg and ladder structure is attained by a simple and economical arrangement.

Thus, while I have illustrated and described the preferred embodiment of my invention, it is to be understood, that this is capable of variation and modification, and I therefore do not wish to be limited to the precise details set forth, but desire to avail myself of such changes and alterations as fall within the purview of the following claims:

I claim:

1. In a ladder-stool, pairs of front and rear legs rigidly connected together at their upper ends, a spreader formed from a metal tube of predetermined diameter and bent to a U-shaped form affording a rear bar and side bars, and said side bars having their ends bent toward each other to afford aligned bearing openings facing toward each other, said spreader being secured to all of said legs with said aligned openings disposed in a horizontal relation between said front

legs, and a step structure having a transverse pivot means fixed thereto and projecting into said bearing openings to pivotally support said step structure between said front legs.

2. In a ladder-stool, pairs of front and rear legs rigidly connected together at their upper ends, a spreader formed from a metal tube of predetermined diameter and bent to a U-shaped form affording a rear bar and side bars, and said side bars having their forward ends bent toward each other to afford aligned bearing openings facing toward each other, said spreader being secured to all of said legs with said aligned openings disposed between said front legs, a step structure comprising a pair of similar frame members each formed from tubular metal and bent to afford a forward leg with a lower step support extended rearwardly therefrom, a riser element extended upwardly from the rear end of the lower step support, and an upper step support extended forwardly from the upper end of said riser, a transverse spacer tube secured to and extended transversely of said frame members at the junctures of said risers and said lower step supports and extended beyond said members to afford bearing journals, said journals projecting into said bearing openings to pivotally support said step structure between said front legs.

3. In a ladder-stool, pairs of front and rear legs rigidly connected together at their upper ends, a spreader member formed from a metal stock of circular cross section and bent to a U-shaped form affording a rear bar and forwardly extended side bars, and said side bars having their forward ends bent toward each other to afford aligned bearing elements facing toward each other, said spreader being secured to all of said legs with said bearing elements disposed on a horizontal axis between said front legs, and a step structure having a transverse pivot member formed from metal stock of circular cross section and fixed thereto to afford projecting elements, one of said members being formed of tubular stock having an internal diameter just larger than the external diameter of the other of said members, and the bearing elements of said other of said members being extended into the open ends of the bearing ele-

ments of said one of said members to pivotally support said step structure between said front legs.

4. In a ladder-stool, pairs of front and rear legs rigidly connected together at their upper ends, a spreader member formed from material of circular cross section and bent to a U-shaped form affording a rear bar and side bars, and said side bars having their forward ends bent toward each other to afford aligned bearing elements facing toward each other, said spreader being secured to all of said legs with said aligned bearing elements disposed between said front legs, a step structure comprising a pair of similar frame members each formed from metal and bent to afford a forward leg with a lower step support extended rearwardly therefrom, a riser element extended upwardly from the rear end of the lower step support, and an upper step support extended forwardly from the upper end of said riser, a transverse spacer member formed of material of circular cross section and secured to and extended transversely of said frame members at the junctures of said risers and said lower step supports and extended beyond said members to afford bearing elements, one of said members being formed from tubular stock having an internal diameter substantially the same as the outer diameter of the other member so that the bearing elements of said one member have open ends and internal bearing surfaces, and the bearing elements of said other member being extended into said open ends to pivotally support said step structure between said front legs.

CHARLES W. HARRISON.
